UNITED STATES PATENT OFFICE.

JAMES R. HUGHES AND WILLIAM H. WEBER, OF SOUTH BEND, INDIANA, ASSIGNEES
TO THE STUDEBAKER CORPORATION, OF SOUTH BEND, INDIANA, A CORPORATION
OF NEW JERSEY.

DESIGN FOR A RADIATOR CAP.

Application filed April 12, 1928. Serial No. 26,304. Term of patent 14 years.

To all whom it may concern:

Be it known that we, JAMES R. HUGHES and WILLIAM H. WEBER, citizens of the United States of America, and residents of South Bend, in the county of St. Joseph and State of Indiana, have invented a new, original, and ornamental Design for a Radiator Cap, of which the following is a specification, reference being had to the accompanying drawing, forming a part thereof.

In the drawing Figure 1 is a side elevation

of the radiator cap, Figure 2 is a front elevation of the radiator cap shown in Figure 1, and Figure 3 is a plan view of the radiator cap shown in Figures 1 and 2.

I claim:

The ornamental design for a radiator cap substantially as shown.

Signed by us at South Bend, Indiana, this 5th day of April, 1928.

JAMES R. HUGHES.
WILLIAM H. WEBER.
